UNITED STATES PATENT OFFICE.

MATHIAS J. HINDEN, OF CLEVELAND, OHIO, ASSIGNOR TO JULIUS KING, OF NEW YORK, N. Y.

DESIGN FOR A FRAME FOR TEST-LENS.

SPECIFICATION forming part of Design No. 25,949, dated August 18, 1896.

Application filed July 6, 1896. Serial No. 598,240. Term of patent 7 years.

To all whom it may concern:

Be it known that I, MATHIAS J. HINDEN, a citizen of the United States, and a resident of Cleveland, in the county of Cuyahoga and State of Ohio, have invented and produced a new and original Design for a Frame for a Test-Lens, of which the following is a specification.

Reference is to be had to the accompanying drawing, which forms a part of this specification, and in which the figure shows in perspective my newly-designed frame for a test-lens used by opticians.

The leading feature in my design consists in a flat annulus, the outer periphery of which at two adjacent points merges into outwardly-extended edges in a plane with the plane of the annulus.

A represents the annulus, whose two opposite surfaces are flat and whose inner edge or periphery *a* is a circle. The outer edge *a* of the annulus A is outwardly extended at two adjacent points *b b*, both in a plane with the plane of the annulus, and these extended edges meet at *c*, so that the whole presents the appearance of a circle within another partial circle, the latter being laterally extended in a plane with the said circles.

What I claim is—

The design for a frame for a test-lens, substantially as herein shown and described.

MATHIAS J. HINDEN.
